UNITED STATES PATENT OFFICE.

PETER EBNER, OF COLUMBUS, OHIO.

LETTER-FILE.

1,091,490.

Specification of Letters Patent.

Patented Mar. 31, 1914.

Application filed August 22, 1912. Serial No. 716,385.

To all whom it may concern:

Be it known that I, PETER EBNER, a citizen of the United States, residing at Columbus, in the county of Franklin and State of Ohio, 5 have invented certain new and useful Improvements in Letter-Files, of which the following is a specification.

My invention relates to letter files and is particularly directed as an improvement in 10 the types of letter files commonly known as the individual letter file.

My aim is to provide a structure which may be readily assembled, as well as comparatively simple to manufacture.

15 I preferably make my letter file of metal and construct the same to be fire proof. Heretofore metal file boxes have been so constructed that when subjected to an intense heat, the joints collapse by either melting 20 the soldering material or warping the same out of shape. To overcome this, I provide a series of interlocking joints so constructed that soldering of the same is not absolutely necessary. These interlocking joints take 25 the form of channel formations formed along the adjoining edges of the sections of the box to be joined together. I preferably make two sides and one end of the box of one sheet of material and bend the edges of 30 the two side pieces back upon themselves to form a seat for complementary oppositely extending formations upon the top and bottom pieces. The top and bottom pieces may then be slid into their correct positions and the 35 edges either clamped into rigid holding relation, or the use of a small portion of solder may be resorted to. It will be noted, that in case of fire, the file box is held intact even 40 should solder be used in its construction, 45 since the interlocking joints prevent collapsing of the same.

I preferably provide my casing with a door or gate forming one end and pivotally mount the same upon one of the side pieces. 5 Within the casing I provide a tray member for the reception of the letters to be filed and it is my object to so construct my letter file to prevent removal of this tray when the same is drawn out in its normal plane. In 10 the present case, the formations carrying the index leaves of the tray member, coact with a reinforcing rib carried along one edge of the casing to prevent its removal. The lower portion of these formations are, however, so formed that by a slight tilting of the tray out of its normal plane, its removal is

permitted. These formations carried by the tray are so formed as to also permit removal of the index leaves if it is desired.

Another object of my invention is to reinforce the open end of the body portion and to use one of these reinforced edges as a keeper coacting with a spring latch carried by the gate and to pivotally mount the gate upon the other reinforced edge. I prefer- 60 ably do this by curling the edge of the open end around a wire and pivotally mount the gate by pintles extending into the curled edge of the opposite side.

The preferred embodiment of my invention is shown in the accompanying drawings, 65 in which similar characters of reference designate corresponding parts, and in which:

Figure 1 is a side view of my letter file, 70 Fig. 2 is a bottom plan view of the same, Fig. 3 is an end elevation of the structure shown in Fig. 1, Fig. 4 is a plan view of the preferred form of my tray, Fig. 5 is a side elevation of the same, Fig. 6 is an enlarged sectional view of the structure shown in Fig. 2, 75 Fig. 7 is a section taken on line 7—7 of Fig. 6, Fig. 8 is a sectional view showing the tray in extended position, and Fig. 9 is a detail view of a portion of the letter file showing 80 the mounting of the gate.

In the drawings, my letter file is shown as comprising a body portion formed of sides 1 and 2 and an end 3 formed from a single sheet of material. Each of the two longitudinal edges of each side is turned back upon itself, as shown at 4, to form channels. Top and bottom pieces 5 and 6 are also formed with channels along their longitudinal edges, but these channels differ slightly from those formed upon the side pieces, in that 85 they are bent outwardly and again inwardly, as shown at 7. The inwardly extending portion fits in the channels formed upon the edges of the side pieces 1 and 2. When assembling, the channels formed upon the 90 members 5 and 6 are made to engage the channels on the pieces 1 and 2. The members 5 and 6 are then slid into position and are limited in this movement by flange formations 8 and 9, integrally carried by the 95 members 5 and 6, by abutting the back 3. My casing is preferably held in assembled condition by clamping the coacting channels into rigid holding engagement. I have found it desirable, however, to solder a small 100 portion of the joint, as shown at 9^a, which prevents vibrating of the joint by continued

use, which would in time weaken the same. The open end of the casing is reinforced by curling the free ends of the sides back upon themselves as shown at 10 and 11. To further reinforce one edge I insert the wire in the curled portion 10 and support a gate 12 upon the other curled edge 11 by the insertion of pintles 13 in the curled edge 14 of the gate after passing through the top and bottom pieces 5 and 6. The curled edge 11 of the casing is partially cut away in a well known manner to accommodate the curled edge 14 of the gate complementally cut away. The other edges of the gate 12 are preferably reinforced by bending the metal back upon itself to form a single hem as best shown at 15. The numeral 16 designates a resilient catch which co-operates with the reinforcing rib 10 for holding the gate in its closed position.

Mounted within the casing is a tray 17 desirably made from a single piece of wire 18 bent to substantially rectangular shape and supporting wire mesh 19 which wire mesh serves as a support for the index leaves 20. The forward end of the wire 18 is bent up as at 21 to form a hand hold and has its free ends bent upwardly and again downwardly to form open ended hook formations 22 as indicated at 22. The index leaves 20 are carried by the open ended hook formations 22 and the removal of the same is possible by removing the tray and completely turning the leaves over backward.

When it is desired to use my letter file, the gate 12 is opened and the tray 17 withdrawn outwardly by gripping the handle portion 21, the hook formations 22 coacting with the reinforcing rib 10 carried by the casing 40 to prevent removal of the tray when drawn out in its normal plane. Upward tilting of the tray will, however, permit of its removal since the free end of the hook formation 22 is not in contacting relation with the side 2 of the casing. After the tray is completely removed in the manner indicated, the index leaves may be removed or replaced as is desired and the tray again inserted within the casing. It will be apparent that I have shown comparatively simple means for accomplishing the objects of my invention.

What I claim is:

1. A letter file comprising a casing, a stop carried by said casing, a removable tray within the casing and formations carried by said tray for removably carrying index leaves and for coacting with said stop to prevent removal of said tray when drawn out in its normal plane and constructed to permit removal of the tray when tilted out of its normal plane.

2. A letter file comprising a casing, a stop carried by said casing, a removable tray within the casing, and formations carried by said tray for removably carrying index leaves, said formations coacting with said stop to prevent removal of said tray when drawn outward in its normal plane.

3. A letter file comprising a casing, a removable tray within said casing, an inwardly extending reinforcing rib on one edge of the end of said casing, and formations carried by said tray for removably carrying index leaves, said formations coacting with said rib to prevent removal of said tray when drawn out in its normal plane, but permitting removal of the tray when tilted out of said normal plane.

4. A letter file comprising a casing, a gate hinged to said casing, an inwardly extending rib on one edge of the open end of said casing, a tray, open ended hook formations carried by said tray for coaction with said rib for preventing removal of the tray when drawn out in its normal plane, said open end permitting removal of the tray when tilted out of its normal plane.

5. A letter file comprising a casing having a body of two sides and one end formed of a single piece of material, the top and bottom edges of said side pieces being doubled back to form hook channels, top and bottom pieces formed with channel formations along their longitudinal edges for engagement with the channels on said side pieces, and flange formations on said top and bottom pieces for engagement with the end of said body.

6. A letter file comprising a body of two sides and one back formed of one piece of material, channel formations along the top and bottom edges of said side pieces, a top piece, a bottom piece, complementary channel formations along the longitudinal edges of said top and bottom pieces mounted in interlocking relation with said first channels, and a gate hingedly mounted on said body.

In testimony whereof I affix my signature in presence of two witnesses.

PETER EBNER.
